United States Patent

Des. 238,943

Patented Feb. 24, 1976

238,943

BUILDING STRUCTURE

William A. Curci, 4947 Fulton Drive NW,
Canton, Ohio 44718

Filed Oct. 26, 1973, Ser. No. 410,196

Term of patent 14 years

Int. Cl. D25—03

U.S. Cl. D13—1 A

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.

FIG. 13.

FIG. 1 is a front perspective view of a first form of the building structure embodying my new design;

FIG. 2 is a front elevation of the building structure shown in FIG. 1;

FIG. 3 is a rear elevation of the building structure shown in FIGS. 1 and 2;

FIG. 4 is a right end view of the building structure shown in FIGS. 1-3;

FIG. 5 is a left end view of the building structure shown in FIGS. 1-4;

FIG. 6 is a plan view of the building structure shown in FIGS. 1-5;

FIG. 7 is a cross-sectional view of the building structure of FIGS. 1-6 taken along plane VII—VII of FIG. 1;

FIG. 8 is a front perspective view of the building structure shown in FIGS. 1-7 illustrating the entrance platform as folded for nonuse;

FIG. 9 is a front perspective view of a second form of the building structure embodying my new design; and

FIG. 10 is a rear perspective view of the building structure shown in FIG. 9;

FIG. 11 is a front perspective view of another form of the building structure embodying my new design;

FIG. 12 is an end elevation of the building structure of FIG. 11; and

FIG. 13 is a rear perspective view of the building structure shown in FIGS. 11 and 12.

I claim:

The ornamental design for a building structure, substantially as shown and described.
